US0D1040394S

(12) **United States Design Patent** (10) **Patent No.:** **US D1,040,394 S**
(45) **Date of Patent:** **** Aug. 27, 2024**

(54) **STRING LIGHT**

(71) Applicant: **Dongguan Meiting Electronic Technology Co., Ltd.**, Dongguan (CN)

(72) Inventor: **Chengwei Song**, Dongguan (CN)

(73) Assignee: **Dongguan Meiting Electronic Technology Co., Ltd.**, Dongguan (CN)

(**) Term: **15 Years**

(21) Appl. No.: **29/869,735**

(22) Filed: **Jan. 6, 2023**

(51) LOC (14) Cl. **26-04**

(52) U.S. Cl.

USPC **D26/25**; D26/60

(57) **CLAIM**

The ornamental design for a string light, as shown and described.

DESCRIPTION

FIG. 1 is a front perspective view of a string light, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of area 9 in FIG. 1;

FIG. 10 is another perspective view thereof, shown in an alternate configuration of use; and,

FIG. 11 is another perspective view thereof, shown in an environment of use.

The broken lines in the drawings illustrate portions of the string light, the dot-dash-dot lines are for annotative purposes, the additional broken lines shown in FIG. 11 represent environment; all broken lines form no part of the claimed design.

1 Claim, 11 Drawing Sheets
